UNITED STATES PATENT OFFICE.

WILLIAM M. HURLEY, OF ROCKLAND, MASSACHUSETTS.

KEYELET.

1,109,647.

Specification of Letters Patent.

Patented Sept. 1, 1914.

Application filed April 6, 1914. Serial No. 829,877.

To all whom it may concern:

Be it known that I, WILLIAM M. HURLEY, a citizen of the United States, residing at Rockland, in the county of Plymouth and State of Massachusetts, have invented an Improvement in Eyelets, of which the following is a specification.

In the manufacture of laced-shoes it is quite popular at the present time to employ what are commonly called invisible eyelets. The common method of making the eyelets invisible is to secure them, in the usual manner, to a facing-strip, and then to arrange said facing-strip on the inside of the top or upper at the side of the front-opening, and so disposing said facing-strip with relation to the top or upper, that the eyelets register with holes formed in the portions at the sides of the front-opening. Eyelets of usual form are employed but in this manner they are concealed from view. This method of concealing the eyelets is expensive as well as objectionable for many reasons.

This invention has for its object the production of an improved form of eyelet having engaging-means extending over the outer and inner sides or faces of the top or upper, thereby to secure it in place, said engaging-means being arranged to admit of the eyelet, for the most part, being concealed in the eyelet-hole, and its exposed portion being arranged to be covered and thereby concealed by the lacing.

In one embodiment of my invention the improved eyelet comprises a tubular body, usually of cylindrical form, the lower end of which may be bent outwardly by pressure to form a flange, substantially the same as has heretofore been done, and the upper end of which has a short narrow neck arranged in continuation of the body, at one side thereof, said neck having at its extremity an outwardly extended ear, which is, or may be, co-extensive with the neck. When this eyelet is set the flange at its lower end will engage the inner face and the ear at its upper end will engage the outer-face of the top or upper; and said ear is arranged on that side of the eyelet-hole next the edge of the front-opening, so that when the lacing is passed through the eyelet, said ear will be covered and thereby concealed by the lacing. The tubular body together with the neck thereon may be made approximately long enough to extend through the eyelet-hole in the top or upper, in which case the upper

end of the tubular body will be arranged below the outer face of said top or upper, or said body and neck may be of lesser length. The neck at the upper end of the body may be reduced in length to such an extent that the ear will be disposed close to the plane of the upper end of the body, or said neck may be entirely omitted, and, in the latter case, the ear will be extended outwardly, directly from the upper end of the body, although arranged in a plane above the upper end of the body a distance equal to the thickness of the ear, thereby to enable the body to occupy a concealed position in the eyelet-hole.

My invention therefore includes within its scope a tubular body of such dimensions as not to project beyond the outer face of the upper, and having an ear at its upper end which extends over the outer face of the material at one end of the eyelet-hole, which ear serves as a co-operating part of the engaging-means for the eyelet.

Figure 1 is a perspective view of the top or upper of a laced-shoe with eyelets embodying this invention. Fig. 2 is a top plan view of one of the side-portions. Fig. 3 is a bottom plan view of one of the side-portions. Fig. 4 is a vertical section of one of the side-portions illustrating the eyelet in vertical section. Fig. 5 is a perspective view of one of the eyelets, and Fig. 6 is a perspective view of a modified form of eyelet embodying my invention.

Referring to the drawings, Figs. 1 to 5, 1 represents the tubular body of the eyelet, here shown as of cylindrical form; 2 is a short neck arranged at the upper end of said body, and 3 is an ear extended outwardly from the upper end of said neck and co-extensive therewith. The tubular body is composed of ductile material admitting of its lower end being bent outwardly during the setting operation to form a flange 4, as has usually been done in the setting of eyelets. When the eyelet is set in the eyelet-hole in the top or upper, the ear 3 engages the outer face and the flange 4 engages the inner-face thereof, thereby clamping the material of the top or upper between them, the ear and flange thus constituting engaging-means or securing-means for the eyelet. The eyelet is set in the hole with its ear arranged at that side of the hole next the edge of the side-portion, so that when the lacing is passed through it, said ear will be covered and thereby concealed by said lac-

ing. In the embodiment of the invention shown in said figures, the neck 2, extends down into the eyelet-hole a short distance so that the upper end of the tubular body terminates below the outer face of the material, but, as above stated, said neck may not only be made of lesser length but may be entirely omitted, and, as represented in Fig. 6, the ear 3, is extended outward directly from the upper end of the tubular body, although arranged in a plane above said end a distance equal to the thickness of the metal composing the ear, and in all instances, the eyelet, for the most part, or at least the tubular body thereof, is concealed in the eyelet-hole.

I claim:-

1. An eyelet consisting of a tubular body having an ear extending outwardly at its upper end which is co-extensive with a portion only thereof and arranged for co-operation with an opposing flange formed by bending outwardly the lower end of said body, thereby to clamp a material between them, substantially as described.
2. An eyelet consisting of a tubular body having an outwardly extended ear at its upper end which is co-extensive with a portion only thereof and arranged in a plane above said upper end of the body, said ear being arranged for co-operation with a flange formed by bending outwardly a lower end of said body, thereby to clamp a

material between them, substantially as described.

3. An eyelet consisting of a tubular body adapted to be arranged in an eyelet-hole and having a narrow ear at its upper end which is adapted to overlie the surface of the material at one side of the eyelet-hole, 40 which ear serves as a co-operative part of the engaging means for the eyelet, substantially as described.

4. An eyelet for laced-shoes consisting of a tubular body adapted to be arranged in an eyelet-hole in the upper at the side of the front opening with its upper end-portion for the most part terminating substantially flush with but not projecting beyond the outer surface of the upper, and having an 50 ear at its upper end which is adapted to extend for a short distance over the outer surface of the upper at that side of the eyelet-hole between said hole and the edge of the portion in which it is set, thereby to be covered by the lacing, said ear serving as a co-operative part of the engaging-means for the eyelet, substantially as described.

In testimony whereof, I have signed my name to this specification, in the presence 60 of two subscribing witnesses.

WILLIAM M. HURLEY.
